United States Patent Office

Des. 211,466
Patented June 18, 1968

211,466

CENTRIFUGE OR SIMILAR ARTICLE

Gerald D. Gulotta, New York, N.Y., assignor to Clay-
Adams, Inc., New York, N.Y., a corporation of New
York

Filed June 28, 1967, Ser. No. 7,622

Term of patent 14 years

(Cl. D16—2)

FIG. 1

FIG. 2

FIG. 3

FIG. 4

FIG. 1 is a perspective view of a centrifuge showing my new design;

FIG. 2 is a top plan view thereof;

FIG. 3 is a side elevation view thereof; and

FIG. 4 is a rear elevation view thereof.

The dominant features of my design are shown in solid lines in the drawings.

I claim:

The ornamental design for a centrifuge or similar article, as shown and described.
